HYGIENIC SYRINGE

Filed April 15, 1948

UNITED STATES PATENT OFFICE

2,531,793

HYGIENIC SYRINGE

Steve Sulek, San Diego, Calif.

Application April 15, 1948, Serial No. 21,243

3 Claims. (Cl. 128—241)

1

My invention relates to hygienic syringes, particularly douche syringes used by women for cleansing the vaginal tract, and its objects are, to provide a more hygienic and satisfactory device than has heretofore been used for this purpose; to dispense with the usual soft bulb of rubber or rubberlike material acting both as a source of liquid supply and discharge receptacle, and in place thereof to supply cleaning syringe means effecting a complete separation of the incoming from the outflowing fluids, while maintaining a constant flow of fresh fluid to the parts to be cleansed; to provide a more thorough means for separating, spraying, flushing and cleansing all of the folds of the vagina, whether the user of the syringe be standing up, sitting down or in a prone position; to provide a self adjusting shield for preventing the escape of the fluids while passing into or out of the vagina when the syringe is in operation whatever may be the position assumed by said user; to supply a feminine douche syringe for the use of female patients in hospitals resulting in their greater comfort, and in a great saving of time and expense in the attendance of nurses, eliminating the use of bed pans and sanitary pads; to allow the use of readily separable plastic parts throughout in place of rubberlike materials, with resulting greater cleanliness and economy; to render all parts of my said device readily accessible for inspection, adjustment, replacement, restoration or repair, and generally to provide a device which is economical of construction, efficient in action and of prolonged life and durability. My invention further consists of other novel features of construction, and combinations and arrangements of parts, illustrated in the drawing and hereinafter more specifically described and claimed.

In the feminine douche syringe now in common use, there is employed a soft synthetic rubber bulb holding about one half pint of liquid, to which is secured a hard rubber nozzle shaped to follow the curve of the vagina when introduced therein. A soft rubber conical shield sliding upon the shank of said nozzle and closely fitting the same, serves to prevent leakage of said liquid from the vaginal tract, in which the liquid is held prior to being returned to the said bulb. Cleansing of said tract is accomplished by introducing said nozzle therein and by squeezing the said bulb to release the contents thereof and to spray and cleanse the folds of the vagina. Upon releasing the pressure of said bulb, the said fluid so used is by suction returned therein, and the

2

syringe is thereupon removed and its contents discharged into the toilet bowl or other receptacle, and the syringe is replenished with clean liquid, and the cleansing process is repeated to the extent necessary or desired. Ordinarily, the said syringe is more conveniently used while the user is upon the toilet seat; but where used upon a patient while in bed by a nurse in a hospital, a bed pan and sanitary pads are required, a time consuming and expensive procedure. All of these disadvantages, however, are overcome in my improved form of syringe, in which, through a novel arrangement of pipes and passageways a constant stream of fluid is made to flow upon and away from the parts to be cleansed. No one, so far as I am aware, prior to my invention has ever employed a form of syringe, whereby a continuous amount of clean liquid could be supplied for cleansing the vaginal tract and thereafter when so used be conducted away therefrom without contact with the clean incoming stream.

Attention is hereby directed to the accompanying drawing, illustrating a preferred form of my invention, in which similar numerals of designation refer to similar parts throughout the several views and in which—

Figure 1 is a side elevation of a syringe embodying my invention, and inlet and outlet fluid conduits connected therewith;

Fig. 2 is an end view of the device shown in Fig. 1, looking in the direction of the arrows 2—2;

Fig. 3 is a longitudinal section on line 3—3 of Fig. 2, looking in the direction of the arrows, and

Fig. 4 is a lateral section on line 4—4 of Fig. 1, looking in the direction of the arrows.

Referring to the drawing, the syringe there shown is composed of the base 5, nozzle pipes 6, 7, 8 and 9, cap 10, shield 11, casing 12, and inlet and outlet conduits 13 and 14, all of which parts are preferably of plastic or other suitable material.

Preferably, the base 5 is in the general form of a truncated cone, having a central passageway 22, and passageways 6a, 7a, 8a and 9a, quadrantly arranged about the same, and aligned respectively with sockets, formed within the tapered end 15a of said base. Press fitted within said sockets are the reduced inner ends of the nozzle pipes 6, 7, 8 and 9, whose reduced outer ends are likewise fitted within similar sockets formed in the cap 10. Diagonally extending through the end wall of said cap, are the orifices 55 A communicating with the sockets of said cap

and with the passageways of said pipes; and diagonally extending through the outer walls of said pipes are the orifices B communicating with the passageways thereof.

Mounted upon the inner portion of said base 5 is the casing 12, having the annular chamber 12a communicating with the passageways 6a, 7a, 8a and 9a, and having partitioned from said chamber and centrally extending therethrough, the tunnel 12b. Preferably for connecting and securing the said casing to the said base, I construct the inner end of said base with the annular recess 15 and shoulder 16, within which is seated the annular inwardly projecting rim 17 of the said casing, an O-ring 18 being installed and compressed within the annular groove 19 in said inner end providing sealing means for said connection. Leading into the side of said casing and integral therewith is the inlet member 20, having the enlarged tip 21, to which may be attached the end of the elastic hose 13 or other conduit leading from a water faucet or other source of liquid supply.

Also, the inner end of said base 5 is constructed with an outlet member, through which continues and extends the central passageway 22 of said base, and the end of which member is shaped to form the enlarged spout 23, to which is attached the end of the elastic hose 14 or other conduit leading to the place of discharge. As shown, the said outlet member is preferably formed with the annular recess 24 and shoulder 25, an O-ring 18 compressed within the annular groove 28 providing sealing means for this connection.

Preferably installed within the chamber 12a and shaped to fit and to conform to the walls thereof is the bag 29 of permeable fabric or other porous material, containing loosely packed antiseptic or contraceptive crystals, grains or substances of like character 30, and allowing the ready passage therethrough of water or other fluids coming from the inlet conduit 13.

In operating my improved device, the inlet conduit 13 is first connected with a water faucet or other source of fluid supply, and the outlet conduit is connected with the toilet seat, chamber vessel or other means of refuse disposal, then upon the nozzle pipes being inserted within the vaginal tract and the shield adjusted, the water or fluid supply is turned on, whereupon by reason of the quadrilateral arrangement of the said pipes and the diagonal arrangement of the orifices A and B, the cleansing fluid coming from the conduit 13 through the contents 30 of the bag 29 is sprayed or impacted upon all of the parts of the said tract, and thereupon the fluid so used is discharged out of the syringe through the conduit 14. Thus there is a constant flow of fresh cleansing fluid into said tract, and discharge of used fluid therefrom, the continuance of which results in the thorough cleansing of all parts thereof.

Preferably the nozzle pipes 6, 7, 8 and 9 are of plastic material, so as to permit the warming and bending thereof to conform to the shape of the vaginal tract. Also, the shield 11 is of preferably plastic material and self adjusting in character so as to make close contact with the outside parts of the body adjacent to the vaginal tract and to prevent escape of the fluid when passing into or out of said tract whatever may be the position of the user of the syringe while it is being employed to cleanse said tract.

My invention may be embodied in other specific forms without departing from the spirit or essential characteristics thereof. The present em- 75

bodiments, as above set forth are therefor to be considered in all respects as illustrative and not restrictive, the scope of my invention being indicated by the appended claims rather than by the foregoing description, and all changes which may come within the meaning and range of equivalency of the claims are therefore intended to be embraced therein.

What I claim and desire to secure by Letters Patent is:

1. In a feminine hygienic vaginal syringe, the combination of a rounded base having inlet passageways and an outlet passageway therethrough, an elongated nozzle formed of spaced perforated pipes each seated in one of said inlet passageways of said base, and located to spray the folds of the vaginal tract when inserted therein; a casing having an annular chamber connected with said base and registering with the inlet passageways thereof; a quantity of antiseptic material installed in said chamber in the path of the incoming fluid and permitting its ready passage therethrough; means for feeding a continuous stream of said incoming fluid into said chamber, and means connected with said outlet passageway of said base for conducting away the used fluids after having been sprayed without being brought into contact with the incoming stream.

2. In a feminine hygienic vaginal syringe, the combination of a rounded base in the form of a truncated cone having inlet passageways and an outlet passageway therethrough, an elongated nozzle formed of equally spaced perforated pipes each seated in one of said inlet passageways of said base, and located to spray the folds of the vaginal tract when inserted therein; a casing having an annular chamber connected with said base and registering with the inlet passageways thereof; a porous bag of antiseptic material installed in said chamber in the path of the incoming fluid and permitting its ready passage therethrough; means for feeding a continuous stream of said incoming fluid into said chamber, and a conduit connected with said outlet passageway of said base for conducting away the used fluids after having been sprayed without being brought into contact with the incoming stream.

3. In a feminine hygienic vaginal syringe, the combination of a rounded base having inlet passageways and an outlet passageway therethrough, an elongated nozzle formed of equally spaced perforated pipes each seated in one of said inlet passageways of said base, and located to spray the folds of the vaginal tract when inserted therein; a casing having an annular chamber connected with said base and registering with the inlet passageways thereof; a quantity of antiseptic material installed in said chamber in the path of the incoming fluid and permitting its ready passage therethrough; means for feeding a continuous stream of said incoming fluid into said chamber, means connected with said outlet passageway of said base for conducting away the used fluids after having been sprayed without being brought into contact with the incoming stream, and a self adjusting shield mounted upon said base and serving upon the insertion of said nozzle as aforesaid to guard the body and to prevent the leakage from said tract of the said fluids.

STEVE SULEK.
